(57) **CLAIM**

The ornamental design for an earphone accessory substantially, as shown and described.

DESCRIPTION

FIG. 1 is an isometric view of an earphone accessory from a first perspective, showing an embodiment of our new design attached to an earphone for a left ear.

FIG. 2 is an isometric view thereof from a second perspective.

FIG. 3 is an isometric view of the earphone accessory from the first perspective showing the earphone accessory detached from the earphone for the left ear.

FIG. 4 is an isometric view thereof from the second perspective.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof.

Another embodiment for a right ear is provided, which is a mirror image of the embodiment for the left ear shown in FIGS. 1 through 10.

FIG. 11 is an isometric view of an earphone accessory from a first perspective, showing another embodiment of our new design attached to an earphone for the left ear.

FIG. 12 is an isometric view thereof from a second perspective.

FIG. 13 is an isometric view of the earphone accessory from the first perspective showing the earphone accessory detached from the earphone for the left ear.

FIG. 14 is an isometric view thereof from the second perspective.

FIG. 15 is a front view thereof.

FIG. 16 is a rear view thereof.

FIG. 17 is a left side view thereof.

FIG. 18 is a right side view thereof.

FIG. 19 is a top view thereof; and,

FIG. 20 is a bottom view thereof.

Another embodiment for a right ear is provided, which is a mirror image of the embodiment for the left ear shown in FIGS. 11 through 20.

Stippling in the drawings represent the three-dimensional contours of the design, and are not intended to indicate surface decoration. The broken lines shown in the drawings
